(57) **CLAIM**

The ornamental design for grout brush, as shown and described.

DESCRIPTION

FIG. 1 is a perspective view of grout brush showing our new design;

FIG. 2 is a right-hand view thereof, the left-hand view being a mirror image;

FIG. 3 is a top view thereof;

FIG. 4 is a front view thereof; and,

FIG. 5 is a back view thereof.

The broken lines showing bristles illustrate portions of the grout brush that form no part of the claimed design.
